INVENTOR

Edson Hartwell

United States Patent Office.

EDSON HARTWELL, OF HUBBARDSTON, MASSACHUSETTS.

Letters Patent No. 92,443, dated July 13, 1869.

IMPROVED ROCKING-CHAIR.

The Schedule referred to in these Letters Patent and making part of the same.

To all whom it may concern:

Be it known that I, EDSON HARTWELL, of Hubbardston, in the county of Worcester, and Commonwealth of Massachusetts, have invented certain new and useful Improvements in Rocking-Chairs; and I do hereby declare that the following is a full, clear, and exact description of the same, reference being had to the accompanying drawings, forming a part of this specification, in which—

Figure 1 represents a side view of a rocking-chair, with my present improvements applied thereto;

Figure 2 represents, upon an enlarged scale, a side view of a detached part;

Figure 3 represents a top or plan view of the parts shown in fig. 2, the said parts being shown separate from each other; and

Figure 4 represents an edge view of the parts as shown in fig. 2.

Figure 5 represents a top or plan view of one of the sides of the lower frame.

To enable those skilled in the art to which my invention belongs, to make and use the same, I will proceed to describe it more in detail.

In the drawings—

A is the seat of the chair, supported by two forked standards B, one at each side.

The upper ends of the forks *a a* are provided with flat horizontal projections *b b*, through which holes *c* are made for receiving the screws, by which the said standards are fastened to the under side of the seat A, the seat being cut out, or recessed, to receive the flat projections *b b* of each standard B.

The lower ends of the standards B are constructed and are supported in the same manner shown and described in a patent previously granted to me, in July, 1868, and therefore no detailed description is necessary in this connection, more than the statement that the lower ends of the standards are rounded off, in

the form shown in dotted lines, fig. 2, the curved ends *d d* projecting through slots, or holes *e e*, in the rocker-plate C, upon which the lower ends of the standards B rock.

The sides D of the lower frame are composed of three pieces, E, E, and F.

The pieces E are curved, to conform to the shape of the seat A.

The centre-pieces F project down, as shown at *f*, the lower end of the projection *f* being grooved out, to fit the side rounds *g*, and upon which they are designed to rest.

By making the upper ends of the stands forked, as shown in the drawings, the seat is supported in a firmer and more secure manner, and, besides, there is less liability of the connections breaking when thus formed.

The upper inner ends of the pieces E E are doweled to the central pieces F, in a secure manner.

The seat A has combined with it two spiral springs G G, for the purpose of retaining the seat of the chair in the position shown in fig. 1, except when the seat is rocked back and forth by the occupant of the chair.

The operation of the springs is the same as in my previously-patented chair.

Having described my improved rocking-chair,

What I claim therein as new, and of my invention, and desire to secure by Letters Patent, is—

1. The forked standards B, when made and combined with the chair, as shown and described.

2. The combination of the pieces E, E, and F, substantially as and for the purposes set forth.

3. The combination of the side projections *f* with the rounds *g*, substantially as described.

EDSON HARTWELL.
